United States Patent Office

Des. 211,012
Patented May 14, 1968

211,012

TELEPHONE BOOTH UNIT

Henry Dreyfuss, South Pasadena, Calif., assignor to Bell
Telephone Laboratories, Incorporated, Murray Hill,
N.J., a corporation of New York

Filed July 3, 1967, Ser. No. 7,678

Term of patent 14 years

(Cl. D13—1)

FIG. 1

Des. 211,012

PAGE 2

FIG. 2

FIG. 3

FIG. 4

FIG. 1 is a front perspective view of a telephone booth unit showing my new design;

FIG. 2 is a top view of the telephone booth unit shown in FIG. 1;

FIG. 3 is a front elevational view of the telephone booth unit shown in FIG. 1; and

FIG. 4 is a perspective view of a second embodiment of a telephone booth unit showing my new design.

The shelf apertures and telephones are shown in broken lines for illustrative purposes only.

The dominant features of my new design reside in the portions shown in full lines on the drawing.

I claim:

The ornamental design for a telephone booth unit, substantially as shown and described.
